United States Patent Office

Des. 209,462
Patented Dec. 5, 1967

209,462

SUGAR BOWL OR SIMILAR ARTICLE

Frank J. Benes, Lancaster, Ohio, assignor to Anchor Hocking Glass Corporation, Lancaster, Ohio, a corporation of Delaware

Original design application Jan. 5, 1966, Ser. No. 468, now Patent No. 207,786, dated May 30, 1967. Divided and this application Dec. 5, 1966, Ser. No. 5,362

Term of patent 14 years

(Cl. D44—15)

FIG. 1 is a side elevational view of a sugar bowl or similar article, showing my new design;

FIG. 2 is a top plan view thereof; and

FIG. 3 is a bottom view thereof.

The present application is a division of my copending application Ser. No. D. 468, filed Jan. 5, 1966, now Patent D. 207,786 of May 30, 1967.

I claim:

The ornamental design for a sugar bowl or similar article, substantially as shown and described.
